GEORGE AGUTTER, OF FOREST HILLS, NEW YORK.

TENNIS RACKET.

1,423,900.

Specification of Letters Patent. Patented July 25, 1922.

Application filed January 6, 1921. Serial No. 435,333.

To all whom it may concern:

Be it known that I, GEORGE AGUTTER, a subject of the King of England, residing at Forest Hills, L. I., in the county of Queens and State of New York, have invented certain new and useful Improvements in Tennis Rackets; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 cation.

The present invention relates, generally, to improvements in tennis rackets and similar devices; and the invention has reference, more particularly, to a construction of 20 racket provided with a novel metallic reinforcing and stiffening member combined with the racket in a novel manner.

The invention has for its principal object to provide the wooden head and handle, constituting the racket frame, with an exteriorly disposed metallic binding and reenforcing member which surrounds the head, and which is provided with a longitudinally extending inwardly projecting rib adapted 30 to be countersunk or dove-tailed into the outer peripheral faces of the head, throat and a portion of the handle of the racket, to the end that said wooden head and throat of the racket frame may be strongly and 35 efficiently reenforced against breakage, and stiffened so as to readily resist any tendency to warp out of true shape, or be otherwise distorted. In addition to the reenforcing and stiffening function of the metallic binding, the same, by reason of its exterior disposition about the head of the racket frame, permits of the racket strings being passed therethrough and over portions of the same, whereby, not only is the metallic binding 40 more firmly held in operative relation to the wooden head, but also the strings are prevented from pulling through or splitting the wooden head, particular when restringing the racket.

50 Another advantage of the exterior relation of the reenforcing metallic binding to the wooden head is that the former protects the latter against wear due to scraping the racket on the ground, as e. g., when the 55 player picks up balls therewith.

Other objects of the present invention, not

at this time more particularly enumerated, will be clearly understood from the following detailed description of the same.

With the various objects of the invention 60 in view, the same consists, primarily, in the novel construction of reenforced racket hereinafter set forth; and, the invention consists, furthermore, in the novel arrangements and combinations of the various devices and 65 parts, as well as in the details of the construction of said parts, all of which will be more fully described in the following specification, and then finally embodied in the 70 claims appended thereto.

The invention is clearly illustrated in the accompanying drawings, in which:—

Figure 1 is a face view of a racket provided with the novel metallic reenforcing member or binding made according to and 75 embodying the principles of my present invention.

Figure 2 is an edge elevation of the same.

Figure 3 is a detail transverse section, taken on line 3—3 in said Figure 1, and 80 drawn on an enlarged scale.

Figure 4 is a detail longitudinal section, taken on line 4—4 in said Figure 2, also drawn on an enlarged scale.

Figure 5 is an enlarged edge face view 85 of a portion of the reinforced head frame with the stringing removed.

Similar characters of reference are employed in all of the hereinabove described views to indicate corresponding parts.

Referring now to said drawings, the reference character 1 indicates the elliptical head frame which is made of wood, and which is merged at its lower end or throat 2, into the handle portion 3. Engaged over 90 the outer peripheral face or edge of said head frame 1 is a metallic reenforcing member or binding 4, which is preferably made of comparatively thin but strong sheet metal pressed or otherwise wrought into the desired cross sectional shape. Said reenforcing member or binding 4 is provided at each longitudinal side with inwardly turned flanges or skirts 5, which, when the binding 95 is in place, project respectively inwardly over the opposite plane faces of the head frame 1. Said reenforcing member or binding 4 is provided, substantially throughout its length, with a longitudinally extending centrally disposed and inwardly depressed 100 or projecting rib or channel portion 6. The outer peripheral face or edge of said wooden 105

head frame 1 is provided with a corresponding longitudinally extending centrally disposed countersunk channel or groove 7 providing a seat within which is received 5 said rib or channel portion 6 when said binding 4 is assembled in operative relation to the racket. The respective ends of said reenforcing member or binding 4, when the latter is assembled with the racket, are 10 carried downwardly about the opposite edges of the head frame 1, and thence are passed along the throat 2 and down the sides of the handle portion 3. At the approaches to the juncture of said handle portion with 15 the head frame, the flanges or skirts 5 of the reenforcing member or binding 4 are spread outwardly, as at 8, to conform to the swelling or curvature of the said parts, and so as to permit of the ends 9 of said reenforcing member or binding being extended 20 for the desired distance downwardly along the sides of the handle portion. The said ends 9 of the reenforcing member or binding 4 are secured to the handle 3 by one 25 or more fastening screws 10, or any other suitable fastening means for anchoring or holding the same in place, whereby the reenforcing or binding member, as a whole, is securely retained in normal and operative 30 assembled relation to the racket body.

The wooden head frame 1 is bored transversely at suitably spaced intervals with stringing openings or holes 11. The said stringing openings or holes 11 are longitudinally and centrally alined relative to each other, as distinguished from the staggered relation heretofore commonly employed. Said metallic reenforcing member or binding 4 is provided with correspondingly located stringing openings or holes 12, which 35 register over the outer ends of the openings or holes 11 of the head frame 1. Said openings or holes 12 of the reenforcing member or binding 4 are located in the bottom of the rib or channel portion 6, and the same are preferably of somewhat larger diameter 40 than are the stringing holes or openings 11, and furthermore said openings or holes 12 are provided at their longitudinally opposite edges with chamfered or rounded lips 45 13, thus eliminating sharp metallic edges which might tend to cut or otherwise injure the gut strings of the racket.

The head frame 1 is strung with the usual 55 interwoven transverse and vertical strings of gut 14 which are passed through certain of the openings or holes 11 and 12 in one direction and then looped over the reenforcing member or binding 4 and back through 60 adjacent openings or holes 12 and 11 in the opposite direction, in the manner more clearly illustrated in Figure 4 of the drawings. As above mentioned, the holes or 65 openings 11 with the alined holes or openings 12 are disposed around the head frame

1 in longitudinal alinement, and not in staggered relation, consequently the strings 14 pull straight through the openings or holes 11, thus minimizing the tendency of the strings to fray or be cut by the edges 70 of the inner ends of the holes or openings 11 thereby lengthening the life of the strings and the serviceableness of the racket. The stated arrangement of the said holes or openings and the strings 14 also renders restringing of the racket more easily and quickly accomplished, whereby time and labor and consequently expense, is saved in the performance of the restringing operations. Since the loops 14' of the strings 14 75 pass over the reenforcing member or binding 4, they additionally serve, when tightened up, to firmly hold the latter in normal operative engagement with the exterior edge of the head frame 1, and securely retained 80 against accidental separation or dislodgement therefrom. Since the said loops 14' of the strings 14 are located in the bottom of the depressed rib or channel portion 6 of said binding or reenforcing member, the 85 said portions of the gut strings are protected, by the bounding shoulders or beads 15 formed by the sides of said rib or channel portion 6, from being struck against objects on and surrounding the court when 90 swinging the racket about, thereby preventing weakening, breaking or other damage or injury being done to the stringing of the racket; and, furthermore, being thus countersunk in the exterior channel of the rib 100 6, the loops 14' are protected against injurious contact with moisture from the hands or fingers of the player.

It will be apparent from the above description, and from an inspection of the accompanying drawings, that the novel construction of reenforcing member or binding 4, is constructed to adequately brace the wooden head frame against torsion or twist 105 due to any tendency of the latter to warp. The principal factor of the construction for accomplishing such purpose is the longitudinally disposed countersunk rib or channel portion 6, which, by reason of being imbedded in the periphery of the head frame, 110 and by reason of the inherent stiffness and strength of such a channel rib structure, easily resists the warping strains and pressures. Without such stiffening rib or channel portion 6, warping or twisting of the 115 head frame 1 might tend to separate or spread apart the side flanges or skirts 5, resulting in loosening the binding 4 to permit lateral play upon the head-frame, which would consequently be free to yield to the 120 warping strains or tendencies, but the provision of such a rib or channel portion 6 in countersunk relation to the head frame affords what may be termed a longitudinally 125 extending stiff and resistant "back-bone" 130

which resists lateral warping strains from either direction.

Of course, it will be clear that ordinary strains produced by forcible contact of the 5 racket with the balls when playing, are firmly resisted by the reenforcing member or binding 4, so that the racket is very efficiently protected by the latter against breakage either at the throat 2, or at any other 10 part of the head frame.

My invention, therefore, provides a racket adapted to give much longer life in service, as well as one which is adequately protected against warping out of true; and, at 15 the same time, the exterior location of the reenforcing member or binding also serves to protect the wood of the head frame against wear; and, by reason of the novel relation of the stringing thereto, the loops of 20 the strings are also protected against accidental injury. It will be observed by reference to the drawings, that the general neat appearance of the ordinary racket is retained by my novel reinforced structure, so 25 that the racket does not in any way possess a freakish appearance, but rather derives an ornamentation or pleasing embellishment by reason of the shaping and location of the reenforcing member or binding 4.

30 I am aware that some changes may be made in the general arrangements and combinations of the several devices and parts, as well as in the details of the construction thereof without departing from the scope of 35 my present invention as set forth in the foregoing specification, and as defined in the appended claims. Hence, I do not limit my invention to the exact arrangements and combinations of the said devices and parts 40 as described in said specification, nor do I confine myself to the exact details of the construction of said parts as illustrated in the accompanying drawings.

I claim:—

45 1. In a racket, the combination with a wooden head frame and depending handle of a reenforcing metallic binding engaged with and surrounding the outer periphery of said head-frame, the ends of said binding 50 being engaged with and secured to the sides of said handle, said binding having on its opposite sides inwardly extending marginal skirts overlapping the sides of said head frame, and a longitudinally extending centrally disposed depressed rib on the inner side of said binding, said rib being countersunk in the outer periphery of said head 55 frame.

60 2. In a racket, the combination with a wooden head frame and depending handle

of a reenforcing metallic binding engaged with and surrounding the outer periphery of said head frame, the ends of said binding being engaged with and secured to the sides of said handle, said binding having 65 on its opposite sides inwardly extending marginal skirts overlapping the sides of said head frame, a longitudinally extending centrally disposed inwardly depressed rib formed in said binding, said rib being countersunk in the outer periphery of said head frame, said head frame having a plurality of longitudinally aligned and spaced stringing holes, and said binding having a plurality of stringing holes of enlarged diameter 70 with inwardly chamfered edges located in the bottom portion of said rib and registered with the outer ends of said head frame stringing holes whereby the strings of the racket may be looped over portions of said 75 binding within the depressed outer side of said rib.

3. The combination with the wooden head frame of a racket of a metallic reenforcing member engaging and surrounding the outer 85 periphery of said head frame, said member having on its opposite sides inwardly extending marginal skirts overlapping the sides of said head frame, and an inwardly projecting longitudinal rib portion connected 90 with said reenforcing member, said rib portion being countersunk in said head frame.

4. In a racket, a wooden head frame provided with a longitudinal channel in its 95 outer periphery, a metallic binding having a central longitudinal depressed rib to project into said head frame channel, and marginal skirt portions connected with the sides of said binding to overlap the sides of said 100 head frame.

5. In a racket having a wooden head frame, a means for reenforcing said frame against distortion, twisting or breakage, said means comprising a metallic binding 105 engaged with the outer periphery of said frame, said binding having a pair of outwardly bowed longitudinal ribs combined with an intermediate inwardly bowed longitudinal rib, and the outer periphery of said 110 head frame being shaped to conform to the inner contour of said binding thus formed.

In testimony, that I claim the invention set forth above I have hereunto set my hand this 20th day of December, 1920.

GEORGE AGUTTER.
